UNITED STATES PATENT OFFICE

155,337

DESIGN FOR AN ELECTRIC LIGHTING FIXTURE

MacInnis M. Dunbar, Highland Park, Ill., as
signor to Lighting Products, Inc., Chicago, Ill.,
a corporation of Illinois

Application March 18, 1947, Serial No. 137,728

Term of patent 7 years

(Cl. D48—23)

To all whom it may concern:

Be it known that I, MacInnis M. Dunbar, a citizen of the United States and a resident of Highland Park, in the county of Lake and State of Illinois, have invented a new, original, and ornamental Design for an Electric Lighting Fixture, of which the following is a specification, reference being had to the accompanying drawing, forming a part thereof.

Figure 1 is a perspective view of an electric lighting fixture, showing my new design; and

Figure 2 is an elevational view of one end of a fixture as shown in Figure 1.

I claim:
The ornamental design for an electric lighting fixture, as shown.

MACINNIS M. DUNBAR.
